ATTORNEY

UNITED STATES PATENT OFFICE.

CHARLES A. ALDEN, OF STEELTON, PENNSYLVANIA.

RAILROAD-FROG.

1,032,577.

Specification of Letters Patent. Patented July 16, 1912.

Application filed February 8, 1912. Serial No. 676,226.

To all whom it may concern:

Be it known that I, CHARLES A. ALDEN, a citizen of the United States, residing at Steelton, in the county of Dauphin and State of Pennsylvania, have invented certain new and useful Improvements in Railroad-Frogs, of which the following is a specification.

This invention relates to that class of railroad frogs wherein the frog point and a lateral tread portion are formed of hard cast metal such as manganese steel and wherein a wing rail is secured to the frog point and the tread portion laterally adjacent the same, the cast metal tread portion forming a lateral continuation of the head of the wing rail.

The object of my invention is to construct a frog of this class so that the frog point and the lateral tread portion may be formed in a single hard metal casting which may be readily adapted to the side of a wing rail and in which the metal of the casting may be more evenly distributed throughout the parts of the casting than heretofore and in which the desired strength in the casting may be obtained from a smaller amount of metal than heretofore and in which the frog point and the lateral tread portion may be supported on a common base forming a part of the casting and being flush with the bottom of the base of the wing rail so that all tread portions of the frog may be supported directly beneath the same on a tie.

With this object in view, the invention consists in the novel construction and combinations of parts which will be hereinafter fully described and particularly claimed.

In the accompanying drawings, illustrating my invention: Figure 1, is a plan view of a railroad frog, showing one form of embodiment of the invention. Fig. 2 is a plan view of the hard metal casting forming the central portion of the frog, detached therefrom. Figs. 3 and 4, are transverse sections, on lines 3—3 and 4—4, respectively, of Fig. 1.

Referring to the drawings, 5 designates the tread-forming point portion of the frog and 6 the laterally disposed wing rails diverging from the frog throat 7. The usual flangeways 8 are formed between the wing rails 6 and the point portion 5 for the reception and guidance of wheel flanges as the wheels pass over the frog; and the free ends of the wing rails are bent and flared

outwardly, at 9, as usual, to direct the wheel flanges to the flangeways 8 as the wheels pass over the frog in the direction toward the point end of the point portion 5.

Each wing rail 6 is formed of a bent railroad rail section comprising, as usual, a head 10, a vertical web 11 and a base 12; and each wing rail 6 is bent outwardly adjacent the frog point to form a recess for the reception of a hard metal rail engaging portion 13, fitted against the inner side of the wing rail and forming a lateral hard metal continuation of the head or tread portion 10 of the wing rail, adjacent the point portion 5 to receive the blows of car wheels passing over the frog.

In accordance with my invention, the point portion 5 and the wing rail engaging portions 13 are formed in a single casting of hard metal, preferably manganese steel, and the detailed construction of the main body of the casting forming the point and wing rail engaging portions is as follows: 15 designates a flat base extending across the space between and having its bottom in the same horizontal plane with the bottoms of the wing rail bases 12 so that the bases 12 and 15 may rest upon underlying cross ties throughout the width of the frog. The lateral portions of the bottom of the base 15 are raised or off-set to receive and rest upon the inner portions of the wing rail bases 12, as shown, in order that the base 15 may be supported by the wing rail bases 12 as well as by the cross ties. The point portion 5 comprises a web 16 rising from the central portion of the base and extending longitudinally of the frog, and a head or tread 17 formed on the top of the web 15. The head 17 is made tapered and increases in width from the frog point toward the heel end of the point portion, and a slight distance back of the frog point, the head 17 extends laterally from each side of the web 16, the lateral extensions increasing in width as the point portion widens. Each wing rail engaging portion 13 comprises a web 18, rising from one side of the base 15 and extending longitudinally of the frog, and a head or tread 19 formed on the top of the web 18 and extending laterally and inwardly therefrom.

In order to properly brace the point portion 5 and wing rail engaging portions 13 against lateral strain, and to support the heads 17 and 19, respectively, thereof, I form ribs or webs 20 and

21 in the casting. The webs 20 extend transversely of the frog between and connect the webs 18, and the webs 20 also connect the bottoms of the heads 19 and base 15. The 5 webs 21 extend transversely between and connect the webs 18 and the webs 16, and the webs 21 also extend vertically between and connect the bottoms of the heads 19 and the base 15, and the webs 21 also extend 10 vertically between and connect the bottom of the head 17 and base 15 where the head 17 extends laterally from the web 16.

The wing rails 6 and the hard metal casting forming the point portion 5 and wing 15 rail engaging portions 13 are secured together by suitable transverse bolts 26, as shown.

The wing rails 6 diverge from the frog throat 7, at 23, to connect to the usual track 20 rails diverging from the wing rails; and leading from the heel end of the point portion 5 are the usual diverging track rails 24.

The heel end of the casting forming the point portion 5 is provided with an extension 25 arranged between and fitted to the track rails 24. The extension 25, the track rails 24 and parts of the wing rails 6 are secured together by bolts 26^a extending transversely through the same, suitable spacing blocks 27 and 28 being interposed between the wing rails 6 and track rails 24, as shown.

I claim:

1. In a railroad frog, a wing rail having 35 a head, a steel casting forming a base plate, a point portion and a wing rail engaging portion, and means for securing said wing rail and said casting together, said wing rail engaging portion comprising a longitudinally-extending web rising from said base plate and having a head formed on the top thereof and extending laterally therefrom and forming a lateral continuation of the head of the wing rail.

45 2. In a railroad frog, a wing rail having a head, a steel casting forming a base plate, a point portion and a wing rail engaging portion, and means for securing said wing rail and said casting together, said point 50 portion comprising a longitudinally-extending web rising from said base plate and having a tapering head formed on the top thereof and extending laterally therefrom.

55 3. In a railroad frog, a wing rail having a head, a steel casting forming a base plate, a point portion and a wing rail engaging portion, and means for securing said wing rail and said casting together, said wing rail engaging portion comprising a longitudinally-extending web rising from said base 60 plate and having a head formed on the top

thereof and extending laterally therefrom and forming a lateral continuation of the head of the wing rail, and said point portion comprising a longitudinally-extending web 65 rising from said base plate and having a tapering head formed on the top thereof and extending laterally therefrom.

4. In a railroad frog, a wing rail having a head, a steel casting forming a base plate, 70 a point portion and a wing rail engaging portion, and means for securing said wing rail and said casting together, said wing rail engaging portion comprising a longitudinally-extending web rising from said base 75 plate and having a head formed on the top thereof and extending laterally therefrom and forming a lateral continuation of the head of the wing rail, and said casting forming transversely-extending webs 80 connecting the web of the wing rail engaging portion and said point portion and supporting the head of the wing rail engaging portion.

5. In a railroad frog, a wing rail having 85 a head, a steel casting forming a base plate, a point portion and a wing rail engaging portion, and means for securing said wing rail and said casting together, said point portion comprising a longitudinally-extending web 90 rising from said base plate and having a tapering head formed on the top thereof and extending laterally therefrom, and said casting forming transversely-extending webs 95 connecting the wing rail engaging portion and the web of the point portion and supporting the head of the point portion.

6. In a railroad frog, a wing rail having a head, a steel casting forming a base plate, a point portion and a wing rail engaging 100 portion, and means for securing said wing rail and said casting together, said wing rail engaging portion comprising a longitudinally-extending web rising from said base 105 plate and having a head formed on the top thereof and extending laterally therefrom and forming a lateral continuation of the head of the wing rail, said point portion comprising a longitudinally-extending web rising from said base plate and having a 110 tapering head formed on the top thereof and extending laterally therefrom, and said casting forming transversely-extending webs connecting the webs of and supporting the heads of said point portion and said wing 115 rail engaging portion.

In testimony whereof I affix my signature in presence of two witnesses.

CHARLES A. ALDEN.
